UNITED STATES PATENT OFFICE.

STEPHEN D. HARTOG, OF ST. LOUIS, MISSOURI.

MACHINE FOR OPERATING ON COMMUTATORS.

1,070,888.

Specification of Letters Patent.

Patented Aug. 19, 1913.

Application filed May 20, 1912. Serial No. 698,662.

To all whom it may concern:

Be it known that I, STEPHEN D. HARTOG, a citizen of the United States, and residing at St. Louis, in the State of Missouri, have 5 invented certain new and useful Improvements in Machines for Operating on Commutators, of which the following is a specification.

This invention relates to a device for cutting down the mica or insulation between the bars of commutators of electrical machinery.

Certain types of electrical machines such as dynamos and motors are provided with 10 commutators composed of copper bars or segments separated by sheets of mica or other insulation, and the current is conducted to and from the machine by brushes bearing upon the commutator. It is found 15 in practice that the copper bars wear down faster than the mica sheets, so that in course of time the mica will project above the copper bars, causing sparking at the brushes. It is not desirable to turn down the entire 20 commutator in a lathe every time this condition of affairs arises, in view of the fact that the commutator may be otherwise entirely true, and it is not desirable to take a cut from the copper bars unless necessary, as 25 this not only results in wearing down of the commutator, but it is difficult to regain the smooth finish of the commutator surface. It has therefore been the practice to dress 30 down the projecting mica by hand with a file. This however is a very laborious task, as an ordinary commutator has a large number 35 of segments, and moreover the use of a hand file rounds off and mutilates the copper bars, thus resulting in an uneven commutator surface.

One of the objects of this invention therefore is to construct a device by means of which the height of the mica or insulation can be reduced rapidly, accurately, and without 45 requiring a large expenditure of manual labor.

Another object is to construct a device which will be in the form of an attachment 50 which can be attached to an ordinary machine tool and operated by power.

Further objects will appear from the detailed description taken in connection with the accompanying drawings in which:

Figure 1 is a side elevation partly in section of a device embodying this invention, 55 Fig. 2 is a section on the line 2-2 Fig. 1,

Fig. 3 is a section on the line 3-3 Fig. 1, Fig. 4 is a plan view of the device with the driving head removed, Fig. 5 is a bottom view of the driving head, and Fig. 6 is a view illustrating the operation of the device. 60

Referring to the accompanying drawings, 10 designates a support or body provided with a transverse guideway for a slide or carrier 11. This slide is slotted to receive a cutter blade 12 which is clamped therein by means of screws, and which is reduced in thickness to form a thin toothed cutting edge as shown in Figs. 1 and 2. A pin 13 on the carrier 11 extends through a slot in the support and is provided at its upper end with a cam roll 14. The support 10 has formed thereon a boss 15 which is formed hollow to provide a bearing for a driving head 16. This driving head is provided 65 with a reduced bearing portion 17 entering the bearing in the boss and is provided at its lower end with an eccentric cam groove 18 engaging the cam roll 14. The boss 15 and the driving head 16 are provided with 70 coöperating raceways arranged to receive balls 19 to form a thrust bearing between the support and the driving head. The boss 15 and the bearing portion 17 are further provided with coöperating raceways for a series 75 of balls 20 which form a circumferential bearing between the support and the driving head. It will be understood that the diameter of the bearing portion 17 is slightly less than the diameter of the bearing in the boss 80 85 90 95 15. The device is assembled by inserting the driving head into the support, placing the balls 19 in position, inserting the balls 20 through an aperture 21 in the boss 15, and closing the aperture by means of a plug 22. The driving head is provided with a tapered shank 23 arranged to be inserted into a tool holder such as a drill press spindle, and the support 10 is provided with tapped holes 24 arranged to receive a 100 threaded rod or the like. If the shank 23 is inserted into a tool holder such as a drill press spindle, and the drill press spindle revolved while the support is held against movement, then the rotation of the driving head will cause rapid reciprocation of the cutter in its guideway.

It will be noted that the balls 19 and 20 provide an accurate and smooth roller bearing between the driving head and the support, and that the series of balls 20 hold 105 the driving head and support together 110

against endwise separation. The driving head can be readily removed by removing the plug 22 and removing the balls 20 through the side aperture 21.

5 Referring now to Fig. 6 in which 30 designates an armature of an electrical machine provided with a commutator 31 and a drive shaft 32, 33 designates a stand or bracket which is arranged to support the 10 armature upon the table of a drill press. It will be understood of course that a pair of end bearings 34 is provided for the armature shaft, and that the caps of these bearings are arranged to grip and frictionally 15 hold the armature shaft. Since however such supporting brackets are of common construction, a detail description will be unnecessary. The object is to provide a stand for supporting the armature and the 20 commutator thereon in proper coöperative relation with respect to the tool holder or drill press spindle. It is possible to support the armature in its own field frame, which may rest on the drill press table or on the 25 floor. The shank 23 is inserted into the drill press spindle 35 and will be frictionally held therein. A rod 36 threaded at its lower end is fastened in one of the tapped holes 24 of the support 10, and this rod is 30 preferably bent laterally as shown at 37 to engage one side of the spindle bearing arm 38 of the drill press and hold the support against rotation. After the device is in position, the commutator is alined with 35 the device so as to position the mica in alinement with the edge of the cutter 12 as shown in Fig. 6. The drill press clutch is now thrown in which causes the cutter to reciprocate rapidly, and the drill press 40 spindle is then depressed so as to cause the cutter to engage the mica as shown in Figs. 2 and 6. This engagement of the cutter will cause the mica to be cut down, the cutter entering between the commutator 45 segments. Each mica strip can in turn be brought beneath the cutter 12 by rotating the armature, the armature being held in position by the frictional engagement of its shaft with the stand bearings. In Fig. 2 50 is illustrated a part of a commutator showing three sheets of mica, the one to the right of the cutter projecting above the commutator, and the one to the left of the cutter having been cut down. The mica is cut 55 down slightly below the surface of the commutator so that the commutator can be used for some time before the copper will wear down below the mica. The drill press spindle can of course be provided with the usual 60 stop for limiting its downward movement so as to limit the depth of the cut. The thickness of the cutter edge is substantially equal to the thickness of the mica, and in practice cutters of different thicknesses are 65 provided, which cutters may be interchange-

ably inserted in the cutter carrier. As the length of the stroke of the cutter can be made sufficient to cover the entire length of the brush surface of the commutator, each mica strip can be cut down by a single operation. It will thus be seen that the operation is exceedingly rapid and efficient. 70

It is obvious that various changes may be made in the details of construction, within the scope of the appended claims, without departing from this invention, and it is therefore to be understood that this invention is not to be limited to the specific construction shown and described. 75

Having thus described the invention what 80 is claimed is:

1. In a device of the class described, the combination with means for supporting a commutator, of a cutter blade having a cutting edge constructed and arranged to enter 85 between the bars of the commutator and reduce the height of the insulation therebetween, means for supporting said cutter to position its cutting edge parallel with the commutator bars and the insulation therebetween, and means for moving said cutter toward and from said commutator. 90

2. In a device of the class described, the combination with means for supporting a commutator, of a cutter blade having a cutting edge constructed to enter between the bars of the commutator and reduce the height of the insulation therebetween, means for supporting said cutter to position 95 its cutting edge along the commutator bars, 100 means for reciprocating said cutter in a path along the commutator bars, and means for moving said cutter toward said commutator.

3. An attachment of the class described 105 comprising a portable support, a cutter on said support, and a rotary member on said support having an operative connection with said cutter and forming a carrier for said attachment. 110

4. An attachment of the class described comprising a portable support, a cutter on said support, and a rotary member on said support having an operative connection with 115 said cutter and constructed to be attached to a driving member, said rotary member forming a carrier for said attachment.

5. An attachment of the class described comprising a portable support having a transverse guideway thereon, a cutter 120 mounted to reciprocate in said guideway, a driving head rotatively mounted in said support and having a driving connection with said cutter, and an attaching shank on said driving head adapted to be attached to 125 a driving member.

6. An attachment of the class described comprising a portable support having a transverse guideway, a cutter mounted on 130 said support to reciprocate in said guide-

- way, a driving head rotatively mounted in said support, an attaching shank on said driving head adapted to be attached to a driving member, and means for removably retaining said driving head in said support. 5
7. An attachment of the class described comprising a portable support having means for attaching it to a driving device, a cutter on said support, a driving head rotatively mounted in said support, and rollers between said driving head and said support forming means for removably retaining said driving head in said support. 10
8. An attachment of the class described comprising a portable support having a guideway thereon, a projecting cutter mounted in said guideway and having a cutting edge extending lengthwise thereof, a rotary driving head on said support adapted to make a driving connection with a driving device when the attachment is attached thereto, and means connecting said driving head with said cutter to cause said driving head to reciprocate said cutter. 15
9. An attachment of the class described comprising a portable support having a guideway thereon, a reciprocating cutter mounted in said guideway and projecting beyond said support in a direction transversely to the line of movement of said cutter, a rotary driving head on said support adapted to make a driving connection with a driving device when the attachment is attached thereto, and an operative connection between said driving head and said cutter constructed to cause said driving head to reciprocate said cutter. 20
10. An attachment of the class described comprising a portable support having a guideway thereon, a reciprocating cutter mounted in said guideway and projecting beyond said support in a direction transversely to the line of movement of said cutter, a rotary driving head on said support adapted to make a driving connection with a driving device and form an attaching carrier for said attachment, and an operative connection between said driving head and said cutter constructed to cause said driving head to reciprocate said cutter. 25
11. An attachment of the class described comprising a portable support having a guideway thereon, a reciprocating cutter mounted in said guideway and projecting beyond said support in a direction transversely to the line of movement of said cutter, a rotary driving head having an attach- 30
- ing shank adapted to be connected to a driving device to form an operative driving connection therewith and carry and support the attachment on said driving device, and an operative connection between said driving head and said cutter constructed to cause said driving head to reciprocate said cutter. 35
12. An attachment of the class described comprising a portable support having a guideway thereon, a reciprocating cutter mounted in said guideway and projecting beyond said support in a direction transversely to the line of movement of said cutter, a rotary driving head extending into said support and having an operative connection with said cutter to reciprocate the same, means connecting said driving head and support constructed to permit said driving head to carry said support, and an attaching shank on said driving head adapted to be connected to a driving device to form an operative driving connection therewith and carry and support the attachment on said driving device. 40
13. An attachment of the class described comprising a portable support having a guideway thereon, a reciprocating cutter mounted in said guideway and projecting beyond said support in a direction transversely to the line of movement of said cutter, and adapted to enter between the bars of a commutator and cut the insulation therebetween, and means on said support for reciprocating said cutter adapted to make a driving connection with a driving device when the attachment is attached thereto. 45
14. An attachment of the class described comprising a portable support having a guideway thereon, a projecting cutter mounted in said guideway and having a cutting edge extending lengthwise thereof and adapted to be positioned along and enter between the bars of a commutator and cut the insulation therebetween, a rotary driving head on said support adapted to make a driving connection with a driving device when the attachment is attached thereto, and means connecting said driving head with said cutter to cause said driving head to reciprocate said cutter. 50
